J. T. DICKMAN ET AL

AUTOMATIC PAPER FEEDER

Filed Sept. 2, 1926

UNITED STATES PATENT OFFICE.

JOHN T. DICKMAN AND THOMAS L. WHEELER, OF LOS ANGELES, CALIFORNIA.

AUTOMATIC PAPER FEEDER.

Application filed September 2, 1926. Serial No. 133,208.

In this specification and the accompanying drawing we will describe and show a preferred form of our invention, and expressly mention certain of its more important objects. We do not limit ourselves to the forms disclosed, however, since various changes and adaptations may be made therein without departing from the essence of our invention as hereinafter claimed; and objects and advantages, other than those expressly mentioned, are included within its scope.

Our invention relates to means for automatically feeding paper sheets for printing, and among its principal objects are; first, to provide an improved device adapted for lifting the central portion of a sheet of paper from a stack of loose sheets to break the effects of static attraction and vacuum; second, to furnish facilities for keeping the sheet stack in contact with a back-stop to preserve alignment of the sheets; third, to supply automatic means for advancing the lifted top sheet at the proper time for printing; and, fourth, to accomplish the above by a relatively simple and inexpensive construction.

Our objects are attained in the manner illustrated in the accompanying drawing wherein—

30 Figure 1 is a perspective view showing a preferred form of our automatic paper feeder by itself;

35 Figure 2 is a side elevation of a portion of a rotary neostyle machine with our invention applied thereto in cooperative relation;

40 Figure 3 is a fragmentary view in elevation of certain of the parts shown in Fig. 2 where the "trigger plate" has been removed; and

Figure 4 is a vertical longitudinal section through the "lifting arms" and "paper table" of the construction shown in Fig. 2.

45 Similar reference numerals refer to similar parts throughout the several views.

We have selected for illustration, as indicated above, a form of our invention that is adapted for use with a rotary neostyle. In such machines the printing stencil or type is mounted upon a cylindrical drum 5 having axial journals 6 that are rotatable in bearings carried by the frame 7 of the machine. The direction of rotation of the drum is indicated by arrow 8. The neostyle is equipped with a paper table 9 on which

the sheets 10 to be printed are stacked. A back-stop for the sheets is usually provided to keep them properly aligned. We prefer to employ for this purpose a back-stop having a slight forward inclination as shown at 11. The reason for this will appear presently.

Our improved paper feeder comprises an upright supporting member 12 of suitable shape. This is provided with bolt holes 13 so that it may be bolted to frame 7, as shown at 14. The supporting member carries a horizontal slotted guide bar 15, attached by screws 8, extending outwardly perpendicular to the axis of drum 5. It also carries an operating arm 16 pivotally attached at 17.

The top and bottom edges of guide bar 15 are rabbeted or flanged as shown at 18, and its slot 19 is intermediately recessed as at 20 to allow for lateral displacement of certain 75 of the working parts.

A trigger plate 21, carrying a trigger 22 pivotally mounted at 23 upon its inner surface, is itself pivotally attached at 24 to the outer face of the guide bar. The forward end of the trigger plate is transversely slotted at 25 and a screw 26 is tapped into the guide bar through slot 25 and limits the angular movement of the trigger plate. A spring 27 engages a pin 28 on the trigger plate and thereby normally holds the plate in an elevated position.

The operating arm 16 has a radial slot 29 at its free extremity, the edges of the slot being formed with flanges 30 adapted to act 90 as guides. This arm also carries on its inner surface a relatively large triangular cam 31 which, as illustrated, may be made of a metallic ribbon having an edge brazed to the arm. The cam has two concaved sides 32 and 33. The contour of these sides is such that they may be respectively engaged by rollers 34 and 35 on the drum of the machine to impart a quick inward and outward movement to the operating arm for each revolution of the drum. The rollers are mounted at the extremities of a bar 36 attached by screws 37 to the end of the drum. Obviously the spacing of the rollers and the positioning of bar 36 may be determined in 105 such manner that the extent and timing of the movements of the operating arm may be made as desired.

By referring to Fig. 2 it will be seen that, with the drum rotating in the direction of 110

arrow 8, the roller 34 will engage cam surface 32 when the former has reached the position shown by dotted circle 38. By the subsequent movement of the drum this roller 5 will cause the operating arm to move inwardly and the cam will assume its inner position shown by dotted lines 39. When roller 34 has passed the cam, as indicated by the dotted circle 40, the roller 35 has 10 reached the position shown by dotted circle 41 and is about ready to engage cam surface 33 to push the cam and its operating arm outwardly. The above sequence of operations is repeated, of course, during each 15 revolution of the drum.

The guide bar 15 carries a reciprocating member 42 which is slidable thereon. This member has positioning flanges 43 engaging rabbets 18, and also a laterally projecting 20 pin 44 within slot 29 of the operating arm engaging flanges 30. Thus the inward and outward movements of the operating arm will cause member 42 to travel back and forth upon the guide bar.

25 Member 42 carries a laterally projecting lug 45 and is provided with a vertical slot 46 contiguous to the lug. It also has a vertical flange 47 contiguous to the other side of the slot. The inner surface of this flange 30 and the opposed vertical surfaces of the lug are adapted to act as guide surfaces for a roller 48 at the end of the lower lifting bar 49. This bar is intermediately pivoted to the lug at 50. A parallel bar 51 above is 35 pivoted to the lug at 52. The free extremities of these two bars are pivoted at 53 and 54 respectively to the paper pick-up device 55. A vertical parallel movement will thus be imparted to the pick-up by vertical movements of roller 48. A spring 56 on lug 45 presses upwardly against parallel bar 51 and tends to hold the pick-up in its elevated position.

40 The paper pick-up may be made in a variety of forms as desired. As illustrated it has opposed horizontal arms 57 at its lower extremity and circular adhesive pads 58 on its under surface at the extremities of the arms. We have found that relatively 45 soft adhesive gelatin is a most satisfactory material to use for these pads. When pressed against a sheet of paper the gelatin will adhere to it quite strongly enough to raise the sheet and hold it suspended for an 50 indefinite time, and yet a quick jerk will readily break the hold of the gelatin and free 55 the sheet.

55 The operation of our invention will be fairly clear from the foregoing description, 60 but there are a few additional points to be noted. The paper pick-up is made to deliver a sudden but light blow upon the top sheet of the paper stack when the pick-up has nearly but not quite reached the outer 65 limit of its travel. This is accomplished by

so positioning roller 48 that it will be constrained to roll over the top surface of trigger 22 on the outer stroke of the reciprocating member 42. On the return inward stroke the roller merely lifts the trigger and 70 passes beneath it.

The paper stack is so arranged on table 9 that the blow of the pick-up will be delivered about in the middle of the paper sheets. This will cause the adhesive pads to lift the 75 top sheet from the stack and move it slightly outwardly. The outward movement of the sheet however is limited by back-stop 11 and the sheet therefore becomes slightly buckled and assumes the shape shown at 80 85 in Fig. 4. Obviously this movement and buckling of the top sheet will immediately break and overcome any effects of static attraction, vacuum, or mechanical adherence of the sheets below. The top sheet is held thus suspended until, on the succeeding inward movement of the pick-up, it is delivered to the printing rollers of the machine. The latter grab the sheet, and jerk it in a downward direction free from the 85 pick-up, when the latter has about reached the inner limit of its travel.

We especially desire to call attention to the fact that, when the top sheet of paper is being moved inwardly toward the printing rolls, it is almost wholly suspended. It does not contact with the sheet below except possibly at the inner and outer edges of the suspended sheet. This very slight contact is insufficient to shift the underlying sheet 95 and, as already noted, there is no other shifting tendency since the electro-static attraction and vacuum effects have been broken by lifting the top sheet in the manner set forth. We also desire to point out that at 100 the time the pick-up strikes its blow, and for a short time thereafter it is moving outwardly. This has the effect of keeping the paper stack against back-stop 11 at all times.

The purpose of mounting trigger 22 upon 110 the pivoted trigger plate 21 is to provide a resiliently yieldable trigger to compensate for varying thicknesses of paper stack 10. In the case of a thick paper stack the paper pick-up can not be depressed so far as in 115 the case of a thin stack. The spring 27 will yield and lower the trigger plate and trigger sufficiently to compensate for the thickness of the paper stack.

Having thus fully described our invention 120 in a manner that will make its construction and operation clear to those familiar with the art involved, we claim:

1. A paper feeder comprising; a longitudinally slotted horizontal guide; a member 125 slidable upon the guide; an intermediately pivoted arm carried by the slidable member adapted to swing in a vertical plane and having one end engaged in said slot; a paper pick-up depending from the free end of said 130

arm; and a trigger cam in said slot whereby the end of the arm engaged therein may be suddenly elevated just prior to the end of the outer stroke of the slidable member.

5. 2. In combination with a back-stop for a stack of paper sheets, a paper feeder comprising; a horizontal guide; a member slidable upon the guide; a depressible paper pick-up carried by the slidable member; and
10 means for suddenly depressing the pick-up just prior to the end of the outer stroke of the slidable member to engage the top sheet of the stack and slightly buckle it against the back-stop.
- 15 3. In combination with a back-stop for a stack of paper sheets, a paper feeder comprising; a horizontal guide; a member slidable upon the guide; a horizontally pivoted arm carried by the slidable member; a paper
20 pick-up depending from said arm; and means for moving said arm to suddenly depress said pick-up just prior to the end of the outer stroke of the slidable member to engage the top sheet of the stack and slightly buckle it against the back-stop.

25 4. A construction as set forth in claim 1 wherein the paper pick-up has an adhesive under surface.

5. A construction as set forth in claim 1

wherein the paper pick-up has an under surface consisting of adhesive gelatine.

6. A construction as set forth in claim 1 wherein the trigger is resiliently positioned to yield vertically when the motion of the pivoted arm is strongly resisted.

7. A construction as set forth in claim 1 wherein the slidable member has cam means associated therewith whereby it may be reciprocated by orbitally rotatable rollers adapted to engage said cam.

8. In combination with a printing machine having a pair of orbitally rotatable rollers; a construction as set forth in claim 1 wherein the slidable member has cam means associated therewith adapted for periodic engagement by said rollers, whereby the slidable member may be reciprocated.

9. In combination with a rotary neostyle or the like having a paper table and a pair of orbitally rotatable rollers; a construction as set forth in claim 1 wherein the pivoted arm extends transversely above the table and the slidable member has cam means associated therewith adapted for periodic engagement by said rollers whereby the slidable member may be reciprocated.

JOHN T. DICKMAN.
